UNITED STATES PATENT OFFICE.

FRANCIS J. FARRA, OF ROCHESTER, MINNESOTA.

SAFETY-HOOK.

1,312,966.

Specification of Letters Patent.

Patented Aug. 12, 1919.

Application filed January 20, 1919. Serial No. 272,091.

To all whom it may concern:

Be it known that I, FRANCIS J. FARRA, a citizen of the United States, residing at Rochester, in the county of Olmsted and 5 State of Minnesota, have invented certain new and useful Improvements in Safety-Hooks, of which the following is a specification.

This invention relates to safety hooks for 10 use for various purposes.

The object of the invention is to so construct such a hook that no spring is necessary to hold it closed and which when closed, and engaged with an object to be secured, 15 cannot accidentally open.

Another object is to so construct such a hook that the pull exerted thereon will operate to hold it closed and yet which may be easily opened for the insertion or removal 20 of a ring or other object.

Another object is to provide a device of this character having no parts likely to be broken or to get out of order.

With the foregoing and other objects in 25 view, which will appear as the description proceeds, the invention resides in the combination and arrangement of parts and in the details of construction hereinafter described and claimed, it being understood that 30 changes in the precise embodiment of the invention herein disclosed may be made within the scope of what is claimed without departing from the spirit of the invention.

In the accompanying drawings:—

35 Figure 1 represents a side elevation of a hook constructed in accordance with this invention shown applied and closed in full lines and open in dotted lines,

Fig. 2 is a rear elevation thereof,

40 Fig. 3 is a vertical section, and

Fig. 4 is an enlarged detail perspective view of one member of the hook.

In the embodiment illustrated, the hook constituting this invention comprises two 45 members 1 and 10, adapted to be pivotally connected. The member 1 comprises two correspondingly shaped bills 2 and 3 connected at their rear upper ends by a cross bar 4, said rear upper ends being provided 50 with registering apertures 5 to receive a pintle 6 for connecting member 1 to member 10. One of the bills of the member 1 is provided at its rear upper end with a forwardly extending arm 7 which is offset in- 55 wardly as shown at 8 to position its free front end directly over the space between

the front ends of the bills 2 and 3, as is shown clearly in Fig. 4, said arm 7 being spaced from said ends a sufficient distance to permit the insertion and removal of a 60 ring R or other object to be secured. This arm 7 projects at its front end a slight distance beyond the outer edges of the front ends of bills 2 and 3 as is shown clearly in Figs. 1 and 3, and preferably has its inner 65 face curved or flared to facilitate the insertion of the object to be secured by the hook.

The cross bar 4 which connects the rear ends of the bills 2 and 3, is preferably thickened and made convex on its inner face as 70 shown at 9 in Fig. 3, the convexity of this bar providing for the swinging of the hook member 1 relative to the member 10 as will be presently described.

The member 10 has a shank 11 and a bill 75 12, both lying in the same plane and which is adapted to be arranged between the bills 2 and 3 of the member 1 and to be pivotally connected at the base of its bill 12 with the member 1 by the pintle 6. The free end of 80 bill 12 projects beyond the free ends of the bills 2 and 3 when the parts are assembled as shown in Fig. 3, and against which the arm 7 is designed to abut when the hook is closed. The hook shaped arms or bills 2 and 3 of 85 member 1 are made wider than the bill 12 of member 10, as is shown clearly in Fig. 3 with their inner edges extended beyond the inner edge of bill 12 so that a ring R or other object to be secured by the hook will 90 rest on these projecting edges and hold the hook in closed position, and when a pull is exerted on said ring, all possibility of the hook opening is thereby prevented.

The member 10 has a recess 13 in its rear 95 edge opposite and extending below the pintle 6 as is shown clearly in Fig. 3 and which is designed to permit member 1 to swing upwardly on its pintle 6 into the position shown in dotted lines in Fig. 1 when it is 100 desired to release the ring R and remove it from the hook.

From the above description it will be obvious that this safety hook is composed of two major parts only, the pintle 6 constituting the 105 third member so that there are no springs to get out of order or any delicate parts liable to become broken thereby greatly prolonging the life of the hook and which is rendered absolutely safe when engaged with an 110 object to be secured, it being impossible to open the hook member 1 as long as a strain

is exerted in the direction of the arrow *a* shown in Fig. 1.

It is of course understood that this hook may be used for any purpose for which it is adapted, it being especially useful for securing mud chains to automobile wheels and various parts of a harness on a horse.

From the foregoing description, taken in connection with the accompanying drawings, the advantages of the construction and of the method of operation will be readily apparent to those skilled in the art to which the invention appertains and while I have described the principle of operation of the invention together with the device which I now consider to be the best embodiment thereof, I desire to have it understood that the device shown is merely illustrative and that such changes may be made as are within the scope of the claimed invention.

Having thus fully described my invention, what I claim as new and desire to secure by Letters Patent, is:—

1. A safety hook comprising two members having bills pivotally connected at their bases with an arm carried by one member and spanning the space between the upper ends of its bill, and spaced from the free end of said bill.

2. A safety hook comprising two members having bills pivotally connected at their bases, an arm carried by the upper end of the pivoted portion of the bill and spanning the space between it and the free end thereof, said arm being spaced vertically from said free bill end and offset laterally to po-

sition it in the path of the free end of the bill of the other member.

3. A safety hook comprising two members, one having a pair of laterally spaced parallel bills connected at the rear edges of one end, one of said connected ends having an arm extending forwardly and spanning the space between it and the free ends of said bills, said arm being laterally offset to position its free end over the space between the free ends of said parallel bills, the other member including a bill pivoted at its base between the connected ends of the first mentioned bills, said bill extending between the parallel bills of the other member and being of less width than said bills.

4. A safety hook comprising two members, one being composed of two correspondingly shaped, laterally spaced parallel bills connected at one end by a cross bar, with an arm projecting forwardly from the connected end of one of said bills and offset laterally inward, the other member comprising a shank having a bill adapted to be mounted between the bills of the first mentioned member and pivoted to the connected end thereof, the free end of the intermediate bill being longer than the free ends of the other bills and designed to abut said arm when the hook is in closed position.

In testimony whereof I affix my signature in presence of two witnesses.

FRANCIS J. FARRA.
